(57) **CLAIM**

The ornamental design for a shoebox, as shown and described.

DESCRIPTION

FIG. 1 is a top perspective view of a shoebox, showing my new design;

FIG. 2 is a bottom perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof;

FIG. 8 is a bottom plan view thereof; and,

FIG. 9 is a top perspective view thereof, in a condition of use.

The broken lines in FIG. 9 depict environmental structure only that form no part of the claimed design.

1 Claim, 9 Drawing Sheets
